SWITCH MECHANISM

Don J. Arneberg and Harold E. Whiting, Milwaukee, and Merlin Y. Turnbull, Brookfield, Wis., assignors to Square D Company, Park Ridge, Ill., a corporation of Michigan

Filed Dec. 4, 1963, Ser. No. 327,952
14 Claims. (Cl. 200—124)

This invention relates to switch mechanisms and is more particularly concerned with a protective switch which will respond to excess current in any one of a plurality of circuits.

It is an object of the present invention to provide a trip free thermal overload switch mechanism which can be manually reset by a single operator, providing the current overload conditions in a plurality of circuits have been corrected and wherein the switch mechanism includes a single actuator having integrally formed levers extending at different angles from one another to provide the trip free and switching functions for the mechanisms.

Another object of the present invention is to provide a tripfree overload relay which has a housing defining a cavity wherein the trip free switch operating mechanism is enclosed and to provide the housing with an external recess which is connected to the internal cavity by a passage in a wall of the housing and which is arranged to removably position a separately enclosed switch, preferably of the snap acting type, which has a contact operator accessible to the passage for actuation by a lever of the operating mechanism disposed within the cavity.

An additional object of the present invention is to provide a trip free melting alloy type overload relay unit with an arrangement for converting the unit from a two to a three element unit.

A further object of the present invention is to provide a trip free melting alloy type overload relay or protective switch which incorporates a novel trip free plunger operated overload mechanism which is arranged to be actuated in response to an overload condition in any one of a plurality of circuits for actuating an operator of a separately enclosed switch which is externally accessible for removal and replacement as a unit and to provide the relay with an opening in a bottom wall which will permit the relay to be readily converted from a two element to a three element melting alloy type overload relay.

Further objects and features of the invention will be readily apparent to those skilled in the art from the specification and appended drawing illustrating certain preferred embodiments in which:

FIG. 1 is a top plan view of the trip free overload relay incorporating the features of the present invention.

FIG. 2 is a side elevational view of the relay in FIG. 1.

FIG. 3 is a bottom plan view of the relay in FIG. 1.

FIG. 4 is a view showing certain internal parts of the relay with a top section of the housing for the relay removed.

FIG. 5 is a cross-sectional view taken along line 5—5 in FIG. 1.

FIG. 6 is a cross-sectional view generally taken along line 6—6 in FIG. 1.

FIGS. 7, 8 and 9 are cross-sectional views taken along lines 7—7 in FIG. 1, respectively showing the position of the relay parts in the tripped position, when the operating plunger is initially and fully depressed, and when the parts are in the reset position.

FIG. 10 is a cross-sectional view taken along line 9—9 in FIG. 1 with the parts of the relay in the tripped position as in FIG. 7.

2

FIGS. 11 and 12 are cross-sectional views taken along line 11—11 in FIG. 1 with the parts of the relay respectively in the position when the operating plunger is initially and fully depressed as in FIG. 8 and in the reset position as in FIG. 9.

FIG. 13 is a view partly in section showing in detail certain of the components of the current responsive means as used in the relay in FIG. 1.

In the drawings, and in FIG. 2 particularly, the protective switch or trip free overload relay includes a housing 20 formed by a pair of mating parts 21 and 22 which are preferably molded of a suitable insulating material. The housing parts 21 and 22 when secured together are mounted on a base 23 and are arranged to define an internal cavity 24 which has a bottom wall 26, shown in FIGS. 7—12, a pair of spaced end walls 28 and 30, shown in FIGS. 1 and 6, and a pair of spaced side walls 32 and 34, shown in FIG. 5. As shown in FIG. 6, a pair of spaced partitions 36 and 38 extending between the side walls 32 and 34 and parallel to the end walls 28 and 30 divide the cavity 24 into three parallel compartments 40, 41 and 42. The end wall 28 and the adjacent side wall 32 of housing parts 21 and 22 are shaped to provide an external recess 44 as shown in FIGS. 2 and 5 in which a separately enclosed snap switch 46 is positioned. As shown in FIGS. 7—9, the side wall 32 of the housing part 22 which forms a portion of the recess 44 is provided with a passage 48 which interconnects the recess 44 with the compartment 40. As shown in FIG. 7, each of the partitions 36 and 38 is provided with a slot 50 extending upwardly from the bottom wall 26 providing a passage extending between the end walls 28 and 30 and transversely to the compartments 40—42. The end walls 28 and 30 of the housing part 22 are respectively provided with slots 51 and 52, as shown in FIGS. 4 and 6, which extend toward the bottom wall 26 and are aligned with the slots 50 in the partitions 36 and 38. The slots 51 and 52 are provided with closed ends to provide stops 53 and 54. The closed ends are preferably provided by the bottom edge of the housing part 21 when the housing parts 21 and 22 are assembled. Each of the compartments 40—42 is respectively provided with shelves 40a, 41a and 42a extending inwardly from the side walls 32 and 34. The shelves 40a, 41a and 42a are coplanar with each other and are vertically spaced beneath the top surfaces of the housing part 21 as shown in FIG. 2. Similarly, coplanar with shelves 40a, 41a and 42a and extending inwardly from side wall 34 are shelves 40b, 41b, and 42b as shown in FIG. 1. The shelves 40a, 40b, 41a, 41b, 42a and 42b are each arranged to support metal conductors 55 which are provided at one end with a threaded opening to receive a screw 56 and on the other end are provided with a suitable means indicated by numeral 57 for securing a current conducting member, not shown, to the conductors 55. The partitions 36 and 38 in housing part 21, as shown in FIGS. 10 and 11, are provided with slots 58a and 60a which extend downwardly toward the bottom wall 26 along an axis that is disposed parallel to the axis of slots 50. The housing part 22 is also provided with slots 58b and 60b which are located as in FIG. 4 to be vertically aligned with slots 58a and 60a. The slots 58a and 58b are arranged to guide one arm 116a of a reset plunger 112 and the slots 60a and 60b are arranged to guide a second arm 116b of the reset plunger 112.

Positioned in the respective compartments 40—42 are melting alloy type current responsive means 40c, 41c and 42c which, as shown in FIG. 1, are secured to respective ones of the conductors 55 by screws 56. Each current responsive means includes a solder type current responsive unit which has a heater element connected in series with a circuit to be monitored. A typical example of

a current responsive unit is disclosed in the Van Valkenburg Patent 1,752,514, issued April 1, 1930. When the current flowing through the monitored circuit and therefore the heating element of the current responsive means exceeds a predetermined value, the solder within the unit melts, permitting a ratchet wheel of the current responsive means in a solid state and surrounds the shaft. Spective current responsive means are designated as 40d, 41d and 42d. Normally the solder of the current responsive means is in a solid state and surrounds the shaft whereon the ratchet wheel is fixed to hold the ratchet wheels 40d-42d against rotation. When the current responsive means, e.g., current responsive means 41c, is subjected to abnormal current flow, the ratchet wheel 41d is free to rotate. After the abnormal current flow ceases, the solder again solidifies to maintain the ratchet wheel 41d against rotation.

Movable within the cavity 24 in the passage defined by the slots 50 in the partitions is a rod-like actuator 62 which is arranged to be guided in a vertical path of movement by slots 51 and 52. The closed ends or stops 53 and 54 of the slots 51 and 52 limit the upward vertical movement of the actuator 62. The actuator, which is preferably formed of a molded insulating material, is rotatable in the slots 51 and 52 and as shown in FIG. 4, is formed to have a plurality of levers or projections integrally formed thereon which are spaced along the longitudinal axis of the actuator 62. These levers include three spaced levers 62a, 62b and 62c which extend in a common plane and which are spaced along the longitudinal axis of the actuator 62 to extend respectively into compartments 40, 41 and 42. Preferably the levers 62a, 62b and 62c are located on the actuator to be proximate the left side of the compartments 40-42 as shown in FIG. 6. The aforementioned plurality of levers on actuator 62 also includes a single lever 62d located substantially at the longitudinal center of the actuator 62 and which is coplanar with levers 62a, b and c and extends in a direction opposite to the direction in which levers 62a, b and c extend, as shown in FIGS. 10-12. The plurality of levers on actuator 62 also includes a lever 62e which extends in a plane perpendicular to the plane of levers 62a, b, c and d and is located longitudinally on the actuator 62 to be in alignment with the passage 48 as shown in FIGS. 7-9. Finally the plurality of levers extending from actuator 62 includes a pair of levers 62f and 62g which are spaced along the longitudinal axis of actuator 62 on opposite sides of lever 62d as in FIG. 4 and are angularly oriented as shown in FIGS. 7-10, to extend in a common plane which is at an acute angle to the plane of levers 62a, b and c and at an obtuse angle from the plane passing through lever 62e and the axis of actuator 62.

A suitable guide slot 64 in housing part 22, which is vertically aligned with lever 62d as shown in FIG. 4, provides a guide for a vertically movable element or slider 66 shown in FIGS. 10-12. The slider 66 is urged into constant engagement with lever 62d by a biasing spring 68 which has one end resting on the bottom surface 26 and its other end in engagement with a spring seat 66a on slider 66. The spring seat 66a is located, as shown in FIG. 12, between a pair of spaced arms 66b and 66c which have their outer surfaces in sliding engagement with the walls of slot 64 for guiding slider 66 in its vertical movement. The arms 66b and 66c are interconnected by a central portion 66d which has its upper surface shaped to provide a surface portion 66e which is in constant engagement with lever 62d and a relieved portion 66f which provides clearance between slider 66 and the actuator 62 when the parts of the device are in the position shown in FIG. 12. The slider 66 and spring 68 comprise a biasing means which constantly urges the actuator 62 upwardly into engagement with stops 53 and 54 and as the slider 66 is arranged to engage the lever 62d at a point spaced from the lon-

gitudinal axis of actuator 62, the actuator 62 is constantly urged in a counter-clockwise direction of rotation as shown in FIGS. 10-12.

In this connection it is to be noted that because the lever 62d is located substantially in the longitudinal center of actuator 62, tilting of the actuator 62 by the biasing means including slider 66 is minimized, and the actuator 62 engages both stops 53 and 54 with a substantially equal pressure.

The housing part 22 is also provided with three guide slots 70a, 70b, and 70c which are respectively vertically aligned with levers 62a, b and c as shown in FIG. 4. Each of these slots 70a, b and c have a movable element or slider therein designated as 72a, b and c. The sliders 72a, b and c which are respectively shown in FIGS. 8, 5 and 10, are constantly biased upwardly by springs 74a, b and c. The springs 74a and c have their respective ends positioned by posts 76a and c extending upwardly in slots 70a and 70c from the bottom wall 26. The spring 74b is positioned by a removable member 78 which is positioned in an opening 80 in the bottom wall 26 at the base of slot 70b, as will be hereinafter described.

Each of the sliders 72a, b and c positions a latching member 82a, b and c. As all of the sliders and latching members are identical, only the slider 72b and the latching member 82b will be described, reference to be had to FIGS. 4, 5 and 13.

As shown in FIG. 4, the slot 70b is provided with oppositely facing grooves 70d adjacent the side wall 34. The slider 72b as shown in FIGS. 5 and 13 has a vertical back portion 84 from which a pair of ribs extend. The ribs are received in grooves 70d for guiding the slider vertically. Extending horizontally from the back portion 84 is a ledge 88 providing a surface that is engageable with lever 62a. Extending outwardly from the back portion 84 in the ledge 88 is an opening 90 and a pair of vertically extending ribs 92 which are disposed on opposite sides of the opening. Depending downwardly from the free ends of ledge 88 is a portion 94 which serves to further guide the slider 72b in the slot 70b. A pair of spaced walls 96 are formed to extend downwardly from the ledge 88 between the back portion 84 and the guide portion 94. The walls 96 are each provided with a notch 98 located at the intersection of the guide portion 94 and the bottom surface of ledge 88 and have a portion removed as at 89 (FIG. 5) to provide a confinement for an end of the spring 74b. The latching member 82b is preferably formed from a single metal part to have a base portion 100 and a latching portion 102. The base portion 100 and latching portion 102 are interconnected by a curved portion 104 which is arranged so the latching portion 102 is non-perpendicular to and slightly inclined toward the base portion 100 at an angle which, as shown in FIG. 13, is 7 degrees. Extending outwardly from the free end of the base portion 100 is a pair of oppositely extending tongues 106 which are arranged to be received in the notches 98 for pivotally positioning the latching member 82b and slider 72b when the base portion 100 is received between the spaced walls 96 and the curved portion 104 extends through opening 90 with the latching portion 102 extending upwardly from the ledge 88. The base portion 100 may also be suitably embossed to provide a seat for the spring 74a which normally urges the base portion into engagement with the bottom surface of the ledge 88 thereby causing the latching portion to be rotated clockwise to an inclined position as shown in the drawings. The latching portion 102 is provided with a pawl 108 which, when the slider is positioned as in FIG. 9, is arranged to engage the ratchet wheel 40d, and when the slider is in the position shown in FIG. 7, is arranged to be positioned above the ratchet wheel 40d. The latching portion also includes a vertically extending reinforcing rib 110 which has its bottom edge

engageable with the upper surface of one of the ribs 92 for limiting the counter clockwise rotation of the latching portion 102 relative to the upper surface of the ledge 88.

The reset plunger 112, preferably formed of a molded insulating material, has a portion externally accessible of the housing 20 and a pair of spaced arms 116a and 116b respectively movable in the slots 58a and 58b and 60a and 60b in the housing parts 21 and 22. The arms are interconnected by a bar 118 (FIG. 10) which is integrally formed with the arms 116a and b and located within the cavity 24. The bar 118 has a downwardly extending post 120 formed thereon at its mid portion which positions a spring 122 which has one end resting on bar 118 and its other end resting on the bottom wall 26. An externally accessible portion 119 on the plunger arms 116a and 116b preferably is formed of a separate part of molded insulating material which is secured to the external ends of arms 116a and b to provide an arrangement whereby both arms 116a and b may be simultaneously moved by an external force against the force of spring 122.

Each of the arms 116a and 116b are identical and hence only arm 116a will be described, reference being had to FIG. 11. The arm 116a has a portion 124 extending perpendicular to bar 118 and aligned with lever 62g. The portion 124 is provided with an upper surface 126 which engages an internal surface providing the ceiling for the cavity 24 to limit the upward vertical movement of the arm 116a by spring 122. The portion 124 also has a notch 128 formed by a vertical side wall 130 and a horizontal ceiling 132 vertically spaced below surface 126.

The vertical side wall 130 is engaged by a vertical portion 134 on the end of lever 62g and the ceiling 132 is arranged to engage a flat end portion 136 on the end of lever 62g which is disposed perpendicular to the vertical portion 134. The vertical movement of the arm 116a in a downward direction is limited by the bar 118 as it engages a portion of the housing part 22.

The separately enclosed snap switch 46 which is most clearly shown in FIGS. 2, 5 and 7-9, is provided with an external housing which is shaped to be received in the external recess 44. The housing is mounted on a base 140 which has a pair of spaced ears 142 arranged to be received in a pair of spaced notches in the base 23 which also supports the housing 22. The base 140 has a bent portion having an opening which receives a bolt 146, shown in FIG. 2, which is threaded into an opening in base 23 for securing the base 140 to base 23. The opening in base 140 is located so the bolt 146 is accessible from the side 32 of the housing 20. As shown in FIG. 7, the snap switch 46 has an actuator 148 extending external to its housing in a position to be partly received in passage 48 when the snap switch is installed in recess 44. The actuator 148 is arranged to move an overcenter snap acting member 150 which has a movable contact 152 on a free end. The movable contact 152 is arranged to engage either of two stationary contacts 154 or 156 and to move therewith between a snap action. The movable contact is electrically connected with a wire connecting terminal 158. Similarly, the stationary contacts 154 and 156 are electrically connected to terminals 160 and 162, as shown in FIG. 2.

When the overload relay is assembled, the spring 68 and slider 66 are positioned in slot 64. The springs 74a and c and the sliders 72a and c, including the associated latching members 82a and c, are similarly positioned in the guide slots 70a and 70c and the plunger return spring 122 is positioned on the bottom wall 26. The actuator 62 is then positioned on the housing part 22 with its respective ends in slots 51 and 56 and its levers 62a, c and d in engagement with sliders 72a, 72c and 66. The upper housing part 21 which includes the assembled plunger 112 is then positioned on the lower 75

housing part 22 which in turn is positioned on the base 23. The assembly of the foregoing parts is completed when a pair of screws 166 as shown in FIG. 6, which pass through mounting bosses 168 on the upper housing part 21 and through openings 171 in recesses 172 in the lower housing part as shown in FIG. 4, are engaged in threaded openings in the base 23. The assembly is then completed when the current responsive means 40c and 42c are secured to conductors 55 so the latching members 82 are in engagement with the ratchet wheels 40d and 42d and the snap switch 46 is installed in recess 44 as when screw 146 is threaded in base 23.

The overload relay 20 when thus assembled will be capable of responding to an excess current condition in only two circuits as the parts providing the overcurrent protection which are intended to be included in the center compartment 41 have been purposely omitted. While the parts which would provide overcurrent protection in the center compartment 41 could have been included during the assembly of the relay 20, in many circuits overcurrent protection in two circuits is in accordance with conventional practices thus the relay 20 will not include an excess of costly components. However, the device can be readily converted from a device which will respond to overcurrent conditions in two circuits to a device which will respond to overcurrent conditions in three circuits with little difficulty, as follows.

As previously described, and as shown in FIGS. 3 and 5, the slot 70b is exposed through an opening 80 in the bottom wall 26 and an opening 170 in the base 23, both of which are rectangular in shape with the opening 170 having a slightly greater width than opening 80. Insertable through the openings 80 and 170 is the member 78 which has a cylindrical portion 176 sized to be received in a counterbored portion of the slot 70b. The portion 176 of member 78 which is received in slot 70b is tubular to provide a confinement and spring seat for one end of the spring 74b. The member 78 is provided with a locking and seating portion 178 located between the portion 176 and a portion 180 extending below the locking portion 178 which, as shown in FIG. 3, at its exposed end has a suitable slot 182 to receive a tool, such as a screw driver, for rotating the member 78. The locking portion 178 is generally rectangular in shape having a width greater than the portion of the opening 70b surrounding the counterbore and less than the opening 170. The portion 178 includes oppositely extending locking and camming portions 184 and 185 having ends 186 and 187 which are provided with a curved surface having a radius centered at the center of the cylindrical outer surface of member 78. Extending inwardly from ends 186 and 187 are oppositely facing notches 188 and 189 which extend from the ends 186 and 187 to the external cylindrical surface of member 78.

The notches 188 and 189 thus divide each of the portions 184 and 185, as shown in FIGS. 3 and 13, into two parts with the parts of the portion 184 designated as 190 and 191 and the parts of portions 185 designated as 192 and 193. The parts 190 and 192 are located at diametrically opposite corners of the locking portion 178 and are substantially rectangular in cross section with the surfaces facing portion 180 in a plane normal to the axis of member 78. The parts 191 and 193 which are disposed at the remaining diametrically opposite corners of the locking portions are formed as inclined resilient lugs with a parallelogram cross-section having end surfaces parallel to the axis of member 78 and side surfaces inclined to the axis of member 78. The intersection of the end surface adjacent the notch 189 and the side surface facing portion 180 is coplanar with the surface of parts 191 and 193 facing portion 180.

As shown in FIG. 3, the base 23 is provided with a pair of raised pimple-like bosses 194 adjacent the longer sides of opening 170. The bosses 194 are located on the centerline of the opening 170 which is perpendicular to the longer sides of the rectangular opening 170 and are

spaced adjacent the longer sides to be received in the notches 188 and 189 when the member 78 is inserted through openings and rotated one quarter turn to the position indicated by broken lines in FIG. 3.

When the relay is converted to a device which will respond to overcurrent conditions in three circuits, the slider 72b including latching member 82b, is inserted through opening 170 and opening 80 into slot 70b. The spring 74b is then positioned in the tubular portion of the upwardly extending cylindrical portion 176 of the removable member 78 with one end of the spring 74b seated on the base of the tubular portion. The assembled spring 74b and removable member 78 is then inserted through opening 170 and opening 80 so that the cylindrical portion 176 is received in the counterbored portion of slot 70b and the free end of the spring is seated upon the base portion 100 of the latching member 82b. When the foregoing is accomplished, a suitable tool such as a screw driver, is inserted into slot 182 and the member 78 is rotated one-quarter turn clockwise, as in FIG. 3. During the rotation of the member 78 the inclined lugs 191 and 193, which are both inclined and flexible, pass over the bosses 194 so that the bosses 194 are received in notches 188 and 189 to maintain the member 78 against rotation, as when the spring 74b urges the member 78 into tight engagement with the base 23. The current responsive element 41c is then positioned in compartment 41 with the ratchet wheel 41d in engagement with the latching portion 102 of the latching member 82b. The current responsive means 41c is secured in position in compartment 41 when the screws 56 are applied to secure the current responsive means 41c to the metal conductors 55. The foregoing will complete the conversion of the relay to a device which will respond to current conditions in three individual circuits.

In view of the foregoing description, the operation of the overload relay is as follows, reference being had to FIGS. 7-12, wherein FIGS. 7 and 10 illustrate the parts of the device when the device is in the tripped position, FIGS. 8 and 11 illustrate the parts after the device has been tripped and the reset plunger 112 is fully depressed to position the parts of the device in the reset position and FIGS. 9 and 12 illustrate the position of the parts of the device in the reset position after the plunger has been released.

As was previously set forth, each of the current responsive means which are positioned in the compartments 40, 41 and 42 includes an element 40c, 41c and 42c which is connected in a circuit to be protected and includes a heater element which in response to an excess current flow in the circuit causes the alloy within the element to become fluid so one of the ratchet wheels 40d, 41d and 42d may rotate. The current responsive means in each of the compartments, 40, 41 and 42, also includes a latching member 82a, 82b and 82c respectively carried by sliders 72a, 72b, and 72c which are biased by springs 74a, 74b and 74c. As the operation of each of the current responsive means is identical, although each is independently operable, the operation of the current responsive means 40c in compartment 40 will be described, as shown in FIGS. 7-9. When parts of the overload relay 20 are in the tripped position, as in FIG. 7, the pawl 108 is disengaged from and positioned above the ratchet wheel 40d by the slider 72a which is moved upwardly by the spring 74a to position the actuator 62 against the stops 53 and 54 in slots 51 and 52. Also when the overload relay 20 is in the tripped position, as shown in FIG. 10, the slider 66 is moved upwardly by spring 68 to urge the actuator 62 into engagement with stops 53 and 54. Each of the springs 74a, 74b and 74c are selected to exert greater force on the sliders 72a, 72b and 72c than is exerted by spring 68 on slider 66. Thus when any of the sliders 72a, b or c is in the position shown in FIG. 7, the actuator 62 will be rotated in a clockwise direction

to a tripped position wherein the surface 134 of levers 62f and 62g engages the surfaces 130 on the portions 124 of the reset plunger 112. When the actuator is in the tripped position, the lever 62e is disengaged from the actuator 48 and the movable contact 152 of the snap switch 46 engages the stationary contact 156 which may be connected in an alarm circuit, not shown, to indicate the relay is in a tripped condition.

When the plunger 112 is depressed from the tripped position, as in FIG. 7, toward the position shown in FIG. 8, the actuator will not rotate from the position shown in FIG. 7. This is accomplished as the ceilings 132 of notches 128 on the arms 116a and 116b engage the flat end surfaces 136 on levers 62f and g and cause the actuator 62 to move downwardly without rotating in slots 51 and 52 to the position shown in FIG. 8 wherein the pawl 108 is beneath the ratchet wheel 40d. The actuator 62 is constantly urged upwardly by the biasing means which includes the sliders which react against levers 62a, b, c and d, so the frictional engagement is maintained between the ceilings 132 and flat end surfaces 136. Thus as long as the downward depressive force is maintained on the plunger 112 to both move and maintain the parts of the device in the position shown in FIG. 8, the actuator 62 will be maintained in the position shown in FIG. 8.

When the depressing force on the plunger 112 is removed, the spring 122 causes the plunger 112 to move upwardly in the guide slots 58a and b and 60a and b, from the position shown in FIG. 8 to the position shown in FIG. 9. The upward movement of the plunger permits the actuator 62 and the sliders 72a, b and c to move upwardly to a position wherein the pawls 108 on the respective latch members move into engagement with the ratchet wheels 40d, 41d and 42d. If any of the ratchet wheels are free to rotate the actuator 62 will be maintained in the position shown in FIG. 8 and will move to the tripped position shown in FIG. 7 because the bias provided by any of the springs 68, a or c exceeds the bias provided by the spring 68. If all of the ratchet wheels 40d, 41d and 42d are nonrotatable, the respective pawls 108 will engage the ratchet wheels and thereby prevent further upward movement of the sliders 72a, b and c. The sliders will be then maintained in the retracted position shown in FIG. 9. The slider 66 which is biased upwardly by spring 68 through lever 62d will cause the actuator 62 to move into engagement with stops 53 and 54 and rotate counterclockwise to the position shown in FIG. 9 wherein the levers 62f and g are out of the path of vertical movement of the notches 128 on the arms 116a and b of the reset plunger and the lever 62e is moved counterclockwise into engagement with the actuator 48. The counterclockwise motion of the lever 62e will cause the actuator 48 to move the snap acting spring 150 of the snap switch 46 so that the movable contact 152 engages the stationary contact 154. The stationary contact may be connected in a suitable circuit, not shown, such as an actuating coil, of a device which is to be controlled by the overload relay according to the present invention. As previously stated, when the actuator is in the reset position shown in FIG. 9, the levers 62f and g are rotated so as to be out of the path of vertical movement of the notches 128 on the reset plunger. Thus when the device is in the reset position, depression of the plunger to the reset position will be without effect, so as to provide the device with a trip free operation.

When the parts of the relay are in the reset position as shown in FIG. 9, and an excess current condition occurs in any of the current responsive devices in compartments 40, 41 and 42, the ratchet wheel associated with the current responsive means 40c, 41c or 42c is free to rotate. The slider which is operatively connected to the released ratchet wheel is now free to move upwardly in its slot from the position shown in FIG. 9 to the position in FIG. 7, wherein the slider engages the lever of the actuator 62

and causes the actuator to rotate and position the parts as in FIG. 7, which has been previously described.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a relay the combination comprising; an actuator bodily movable in a vertical path and rotatable about a horizontal axis between a tripped position and a reset position, stop means for limiting vertical movement of the actuator in one direction, a first and a second biasing means each arranged for moving the actuator in said one direction into engagement with the stop means and each arranged for simultaneously urging the actuator in opposite directions of rotation, said first biasing means being arranged to urge the actuator toward the reset position and including at least one vertically movable element having a constant engagement with a portion of the actuator, said second biasing means including a plurality of vertically movable biasing elements each engaging a different portion of the actuator at spaced intervals along the horizontal axis of the actuator, each of the elements of said second biasing means being movable from a reset position to a tripped position wherein the element engages a lever portion and is effective to rotate the actuator to the tripped position while the actuator is in engagement with the stop means and is biased toward the reset position by the first biasing means, a releasable latch for each of the elements of the second biasing means, each of said latch means being arranged when latched for maintaining the element associated therewith in the reset position and out of engagement with the lever portion of the actuator when the actuator is in engagement with the stop means whereby said actuator is rotated to the reset position by the first biasing means, each of said latch means being ineffective when released to prevent movement of the element associated therewith toward the tripped position whereby the actuator is rotated to the tripped position by said element, and a plunger vertically movable from an at rest position having a portion engageable with a portion of the actuator only when the actuator is in the tripped position, said plunger having a biasing means for constantly urging the plunger toward the at rest position, said engageable portions of the actuator and the plunger being arranged so the actuator is constantly maintained in the tripped position and in engagement with the plunger when the actuator is moved by the plunger along its vertical path of movement out of engagement with the stop means to a position wherein any previously tripped element of the second biasing means is moved from the tripped position to the reset position, said engageable portions on the actuator and plunger also being arranged so the actuator is moved to the reset position by said first biasing means when all of the elements of the second biasing means are maintained in the reset position by the latching means and the force on the plunger is released.

2. In a relay the combination comprising; a rod-like actuator bodily movable in a vertical path and rotatable about a horizontal axis between a tripped position and a reset position, a plurality of lever-like portions extending from said actuator, stop means for limiting vertical movement of the actuator in one direction, a first and a second biasing means each arranged for engaging different lever portions of the actuator for moving the actuator in said one direction into engagement with the stop means and each arranged for simultaneously urging the actuator in opposite directions of rotation when the actuator is in engagement with the stop means, said first biasing means being arranged to urge the actuator toward the reset position and including at least one vertically movable element having a constant engagement with a lever portion of the actuator, said second biasing means including

a plurality of vertically movable biasing elements each engaging a different lever portion of the actuator at spaced intervals along the horizontal axis of the actuator, each of the elements of said second biasing means being movable from a reset position to a tripped position wherein the element engages a lever portion and is effective to rotate the actuator to the tripped position while the actuator is in engagement with the stop means and is biased toward the reset position by the first biasing means, a releasable latch for each of the elements of the second biasing means, each of said latch means being arranged when latched for maintaining the element associated therewith in the reset position and out of engagement with the lever portion of the actuator when the actuator is in engagement with the stop means whereby said actuator is rotated to the reset position by the first biasing means, each of said latch means also being ineffective when released to prevent movement of the element associated therewith toward the tripped position whereby the actuator is rotated to the tripped position by said element, and a plunger vertically movable from an at rest position along an axis parallel to the vertical path of movement of the actuator and having a portion engageable with another lever portion of the actuator only when the actuator is in the tripped position, said plunger having a biasing means for constantly urging the plunger in said one direction, said engageable portions of the actuator and the lever portion of the plunger being arranged so the actuator is constantly maintained in the tripped position and in engagement with the lever portions of the plunger when the actuator is moved by the plunger along its vertical path of movement out of engagement with the stop means when the plunger is depressed by a force which is maintained against the biasing means of the plunger for moving the plunger from the at rest position to a position wherein any previously tripped element of the second biasing means is moved from the tripped position to the reset position, said engageable portions on the actuator and the lever portions on the plunger also being arranged so the actuator is moved to the reset position by said first biasing means when all of the elements of the second biasing means are maintained in the reset position by the latching means and the force on the plunger is released and its biasing means moves the plunger toward the at rest position.

3. In a trip free overload relay, the combination comprising; a housing providing an internal cavity, an actuator guided for vertical movement in the cavity, stop means for limiting said movement of the actuator in one direction, said actuator being rotatable in the cavity and having a plurality of spaced levers extending in a common direction and at least one lever extending in a direction opposite said common direction, a first biasing means engageable with said oppositely extending lever for urging the actuator in one direction of rotation and in a vertical direction into engagement with the stop means, a plurality of current responsive second biasing means each having; a spring biased portion within the cavity engageable with one of the plurality of levers of the actuator and movable between a tripped and reset position and biased for moving the actuator into engagement with the stop means and for rotating the actuator in opposition to said first biasing means in a direction opposite to said one direction of rotation, a releasable latch means for maintaining said spring biased portion in a reset position, a vertically movable spring biased reset plunger, cooperating portions on the reset plunger and actuator arranged for mutual engagement and for limiting rotational movement of the actuator to one rotational position by the second biasing means, said cooperating portions of the actuator and the plunger being arranged so the actuator is constantly maintained in the said one rotational position and in engagement with the plunger when the plunger is depressed for vertically moving the plunger and the actuator out of engagement with the stop means and for moving the spring biased portions of the current responsive second biasing means to the reset position, said cooperating portions on

the plunger and actuator also being arranged so the actuator is moved against the stop means by said first biasing means when all of the spring biased portion means are in the reset position and the force on the plunger is released.

4. The combination as recited in claim 3 wherein the cavity is provided with an opening in a bottom wall through which only one of the spring biased portions may be inserted and wherein the housing is provided with a top surface having means thereon for securing the current responsive releasable latch means.

5. The combination as recited in claim 3 wherein a separately enclosed snap switch is received in an externally accessible recess in the housing and wherein the switch has an actuator in engagement with a lever on the actuator.

6. In a current responsive means for an overload relay, the combination comprising: a fusible alloy type current responsive element having a normally fixed ratchet wheel which is rotatable when an excess current passes through the element, a slider having a first portion guided from movement between two positions in the housing by a slot formed in a portion of a housing for the relay and a second portion providing an upper surface facing the ratchet wheel and a lower surface facing away from the ratchet wheel, an L-shaped latching member having a base portion juxtaposed to the lower surface and having a first end pivoted on a portion of the lower surface, said latching member also having a latching portion extending upwardly from a second end of the base portion which is disposed remote from the first end at an angle inclined to the upper surface when the base portion is in engagement with the lower surface, and a pawl on said latching portion arranged to engage the ratchet wheel when the slider is in one of its two positions, and a spring having one end in engagement with a portion of the base portion disposed between the first and second ends and arranged to constantly urge the base portion on its pivot into engagement with the lower surface and bias the slider to a second of its two positions.

7. The combination as recited in claim 6 wherein the base portion and the latching portion of the latching member are interconnected by a curved portion which extends through an opening between the first and second portions of the slider.

8. In a relay the combination comprising: a housing having an internal cavity and an external recess with a passage extending between the cavity and recess, a separately enclosed snap switch removably secured within the recess, said switch having an outer wall forming a continuation of an outer wall of the housing and a contact actuator exposed to the passage when the switch is positioned in the recess, a plurality of current responsive means each including a movable element positioned within the cavity and an actuator movable within the cavity, said actuator having individual portions engaged by the respective elements of each of the current responsive means and having an additional portion disposed to move into engagement and actuate the contact actuator of the switch in response to the operation of any one of the elements of the current responsive means.

9. The combination as recited in claim 8 wherein the housing has an opening in its bottom wall for passing the movable element of only one of the current responsive means into position in the cavity.

10. In a relay the combination comprising: a housing having an internal cavity with at least two partitions extending perpendicular to a bottom and top wall of the housing thereby dividing the cavity into three spaced compartments, a current responsive means in each of the compartments, each of said current responsive means including a current responsive element mounted on the top wall and a spring biased latch means having a portion linearly movable between the top and the bottom walls and a portion engageable with the current responsive element,

a passage in the bottom wall extending from the exterior of the housing into one of said compartments for passing one of the latch means through said passage into the said one compartment and a cover closing said passage when the said one latch means is positioned in the said one compartment.

11. In a relay the combination comprising, a housing having an internal cavity with a bottom wall and partitions dividing the cavity into a plurality of compartments, 10 a unitary actuator vertically movable in the housing and extending transversely across all of the compartments, a plurality of levers integrally formed and spaced on the actuator each aligned for movement in one of the compartments, a current responsive current means individual 15 to each of the compartments, each of said current responsive means including a member having a portion engageable with one of the levers to move said actuator to a tripped position and a portion having a latching surface thereon, and a current responsive element having a releasable portion engageable by the latching surface of said member for maintaining the member in a reset position during normal conditions of current flow and for releasing said latching surface during abnormal conditions of current flow.

12. In a trip free overload relay, the combination comprising: a housing having an internal cavity defined by a bottom wall, a pair of parallel end walls, a pair of parallel side walls, and a pair of spaced partitions extending between the side walls and parallel to the end walls dividing the cavity into three parallel compartments, a rotatable rod-like actuator extending between the end walls and transversely to the compartments, a pair of slots in the end walls for guiding the actuator along a path of movement perpendicular to the bottom wall and arranged to provide stops for limiting the movement of the actuator in a direction away from the bottom wall, a plurality of levers integrally formed on the rod-like actuator, said levers comprising; three spaced levers 35 extending in a common plane and each arranged to extend into one of the compartments, a first single lever centrally located on the actuator and extending in a direction opposite to the three levers, a second single lever extending perpendicular to the plane of said three levers and located on the actuator to be in alignment with the passage and a pair of levers spaced on opposite sides of the first single lever and extending in a plane disposed at an acute angle from the plane of the three levers and at an angle obtuse from the second single lever, a first and a second biasing means each arranged for moving the actuator in the slots into engagement with the stops and each arranged for simultaneously urging the actuator in opposite directions of rotation, said first biasing means including a spring biased vertically movable element in constant engagement with the first lever and arranged for rotating the actuator to a reset position, said second biasing means including a current responsive means in each compartment with each of the current responsive means including a ratchet wheel fusible alloy type current responsive element and a spring biased latch means having a first portion engageable with and arranged to be releasably held by the ratchet wheel and a second portion engageable with one of the levers of the set of levers, each of said current responsive means being arranged to be held in the reset position when the first portion is held by the ratchet wheel and to move the actuator into engagement with the stops and rotate the actuator in opposition to the first biasing means to a tripped position when the first portion is released from the ratchet wheel in response to an excess current flow through the current responsive element, a spring biased plunger externally accessible of the housing having a pair of spaced arms movable in a plane perpendicular to the bottom wall and parallel to the path of movement of the actuator, said arms being spaced to engage the levers of said pair of levers of the

actuator only when the actuator is in the tripped position and having a notched portion arranged to engage a flat end portion on an end of each of the levers for limiting rotational movement of the actuator to the tripped position, said notched and flat end portions being arranged so the actuator is constantly maintained in the tripped position when the plunger is depressed against the bias of said first and second bias means for vertically moving the plunger and the actuator out of engagement with the stops and for moving the second bias means to the reset position, said notched and flat end portions also being arranged so the actuator is rotated and moved by said first bias means into engagement with the stops and rotated to the reset position when all of the current responsive means are held in the reset position and the depressing force on the plunger is released.

13. The combination as recited in claim 12 which includes a cover which closes an opening in the bottom wall of the housing which extends into the internal cavity and exposes the central compartment of the three parallel compartments to the exterior of the bottom wall when the cover is detached from said opening, said opening being sized and located to permit insertion of the latch means of the current responsive means into position in said central compartment and a portion on the cover

10

providing a seat for a spring portion of the latch means when the latch means is installed in the central compartment and the cover is closing the opening.

14. The combination as set forth in claim 12 which includes a separately enclosed switch which is removably secured in an external recess in the housing, said switch having contacts movable with a snap action and an operator positioned for engagement by the second single lever for actuating the contacts of the switch when the actuator is rotated to the reset position.
